MINIMIZED DRAG TOW TARGET CONSTRUCTION

Edward Frey, Akron, Ohio, assignor to The Massillon-Cleveland-Akron Sign Company, Massillon, Ohio, a corporation of Ohio

Application May 4, 1956, Serial No. 582,749

3 Claims. (Cl. 139—419)

The invention relates to minimized drag tow target construction of the banner type, and constitutes improvements of the tow target construction set forth in my prior application for United States Letters Patent, Serial No. 554,977, filed December 23, 1955, now Patent No. 2,807,287.

Banner type tow targets are used for training Armed Forces personnel in gun, cannon, rocket, and missile marksmanship. A banner type tow target for such purpose is connected by a tow line of required length to a towing aircraft. The marksman trainee operates from another aircraft miles away. The aircraft bearing the marksman trainee is termed herein a "weapon system" for convenience, but actually may be any type of aircraft, from a low-powered, low-speed training plane, to a high-powered, high-speed fighter plane.

Prior to the banner type tow target construction set forth in my said application for United States Letters Patent, Serial No. 554,977, now U.S. Patent No. 2,807,287, difficulties have been encountered in producing banner type tow targets having a useful life of sufficient length to minimize the cost of each training mission, and which are otherwise satisfactory, even at relatively low altitudes and low speeds of tow target travel.

Prior banner type tow targets have been made of various types of open mesh flexible fabric material and have been upwards of nine (9) feet wide by forty-five (45) feet long. The forward end of the target may be termed the leading edge, and is connected by a hitch to the rear end of the tow line. The rear end of the tow target may be termed the trailing edge.

In use, the forward portion of a banner type tow target assumes a more or less flat horizontal position which extends to as much as one-third ($\frac{1}{3}$) of the total length of the target. The middle portion of the target, which may extend another one-third ($\frac{1}{3}$) of the total length of the target, assumes a condition of rippling in undulating waves having peaks and valleys which extend transversely of the direction of flight. The rear portion of the target, which may extend the final one-third ($\frac{1}{3}$) of the total length of the target, assumes a condition of whipping or flapping, which is very damaging to the material of the target in this whipping portion of the target.

The difficulties encountered in prior banner type tow target constructions include the following:

First: For the purpose of minimizing the power required in the towing airplane, it is desirable to minimize the total drag of the target. A target made of material having a weight sufficient to reduce rippling and whipping to a satisfactory degree, has a drag which becomes prohibitive.

Second: As the speed of the tow target is increased for training marksmen operating from the higher speed "weapon systems," the greater the increase in target speed, the greater the drag created by the undesirable rippling and whipping of the target.

Third: (1) A high speed "weapon system" is manu-

ally or automatically controlled until contact is made with the target, then a radar operated electronic control system locks on the target, and operates the "weapon system," until the target has been fired on, or passed by.

5 Personnel operating a "weapon system" must be trained in carrying out the "weapon system" objective. (2) Tow targets of prior construction frequently have been made of materials having no radar reflecting properties. To overcome this, radar reflecting corners have been attached to the forward end of such targets, with results that have not been satisfactory. Corner reflectors create greatly increased drag on the tow airplane, and have limiting factors undesirably affecting present radar and fire control systems. (3) Prior banner type tow targets

10 which have been made of metallized fabrics have been excessive in weight and drag, and have been subject to operational objections similar to those incident to the use of radar reflecting corners.

Banner type tow targets including the improvements 15 set forth in my said prior application for United States Letters Patent, Serial No. 554,977, fly satisfactorily at a true air speed of 385 miles per hour at altitudes as high as 30,000 feet.

Requirements of the Armed Forces for 1956 and thereafter, specify a banner type tow target which will fly 20 at altitudes of 30,000 feet and upwards, at indicated air speeds of 250 knots per hour and upwards, with the required durability and low drag characteristics; and such a tow target must be made of material that is radar reflective.

The objects of the present invention include the provision of a banner type tow target including certain of the improvements of my said prior application for United States Letters Patent, Serial No. 554,977, and including 25 other improvements enabling the tow target to meet the requirements of the Armed Forces for 1956 and thereafter, as above set forth.

A further object of the present invention is the provision of such a banner type tow target which may be 30 made of differential weave open woven fabric in continuous lengths without cross-seams.

A further object of the present invention is the provision of such a banner type tow target made of woven fabric, and which is metallized in a manner so as to produce 35 a target which has the desired radar reflectivity and is still within required weight and drag limitations.

The foregoing and other objects are attained by the banner type tow target construction, parts, combinations, and sub-combinations, which comprise the present invention or discovery, the nature of which is set forth in the following general statement, and preferred embodiments of which, together with their mode of use, are set forth by way of example in the following description, and which are particularly and distinctly pointed out and 55 set forth in the appended claims forming part hereof.

The nature of the improvements of the present invention may be described in general terms as constituting tow target construction including side by side seam connected continuous flexible panels, each panel including longitudinally extending laterally spaced warp strands and longitudinally spaced filling strands continuously woven with the warp strands.

Each warp strand is monofilament. The filling strands in one end portion or section of the continuous panel are 60 all monofilament filling strands; and the filling strands in the other end portion or section of the continuous panel are alternate sets of monofilament filling strands, and alternate sets of multi-filament filling strands. Thus, each panel constitutes a differential weave continuous open woven fabric panel including one panel portion or section having monofilament warp strands and monofilament filling strands, and another panel portion or section

having monofilament warp strands and alternate sets of monofilament filling strands and alternate sets of multi-filament filling strands. Preferably the warp strands are arranged in narrower side bands and a center band and wider bands between each side band and the center band, and the warp strands in the narrower bands including pairs adjacent each other and forming a smaller mesh weave than the weave of the wider bands.

By way of example, embodiments of the improved banner type tow-target construction and parts of the present invention are illustrated in the accompanying drawings forming part hereof, in which

Fig. 1 is a reduced plan view, diagrammatic in part, showing a banner type tow-target including the improved differential weave fabric of the present invention.

Fig. 2 is an enlarged fragmentary plan view showing a detached area of the first leading portion or section of the improved banner type tow-target, the first leading target portion or section having a first woven fabric construction.

Fig. 3 is an enlarged fragmentary plan view showing a detached area of the second trailing portion or section of the improved banner type tow-target, the second trailing target portion or section having a second woven fabric construction.

Fig. 4 is a reduced fragmentary diagrammatic plan view of a length of a panel of the improved fabric for the improved banner type tow-target showing the transverse continuous junction between the first and second target portions or sections, and other details.

Fig. 5 is an enlarged fragmentary plan view showing a detached area of the transverse continuous junction between the first and second target portions or sections, and areas of the first and second target portions adjacent the junction.

Similar numerals refer to similar parts throughout the several views of the drawings.

The banner type tow-target shown in Fig. 1 is indicated generally by 10, and constitutes a preferred embodiment of the present invention or discovery.

The tow-target 10 is made of a single ply of improved flexible open mesh differential weave fabric hereinafter described in detail, and is an elongated rectangle of such fabric which may have a width of nine (9) feet and a length of from thirty (30) to forty-five (45) feet in certain targets.

The elongated rectangular tow-target 10 includes a leading edge 11, a trailing edge 12, and transversely spaced side edges 13 and 14. A hitch 15 connects the leading edge 11 in a usual manner with the trailing end of a tow line, not shown, which extends for a mile, more or less, from a usual towing aircraft, not shown.

The tow-target 10 is constituted, from the over-all standpoint, by a first leading target portion or section 16 having a transverse junction indicated by the dot-dash line 17 with a second trailing target portion or section 18.

As shown, the tow-target 10, divided over-all into the first and second portions or sections 16 and 18, is made of three continuous longitudinally extending fabric panels including a side panel 19 having the outer side edge 13, and at its other edge an inside connecting seam S-1 with one edge of a center panel 20. The other edge of the center panel 20 has an inside connecting seam S-2 with a side panel 21 which has the outer side edge 14.

First: Each of the three panels 19, 20, and 21, in the first leading target portion or section 16, is constituted throughout the major portion of its area, by a first woven fabric construction indicated generally by 22, and shown enlarged in Fig. 2.

Second: Each of the three panels 19, 20, and 21, in the second trailing target portion or section 18 is constituted throughout the major portion of its area, by a second woven fabric construction indicated generally by 23, and shown enlarged in Fig. 3.

In each panel 19, 20, or 21, each of the first and second woven fabric constructions 22 and 23 has a different weave structure than the other, constituted by common warp strands 24a and 24b, and by different filling strands.

5 The first woven fabric construction 22 in any panel such as 19 includes a continuous filling strand 25 and a continuous filling strand 26. The diameter of the strand 25 is less than the diameter of the strand 26.

The second woven fabric construction 23 in the panel 19, includes a continuous filling strand 27 having a diameter which is the least diameter of any filling strand in the entire panel. The diameter of the strand 27 may be the same as the diameter of the strand 25, and the strand 27 preferably is continuous with the strand 25.

15 A fragment of one of the panels of the target 10, such as the panel 19, is shown diagrammatically in Fig. 4, at the transverse continuous junction between the first target portion or section 16 and the second target portion or section 18. In this diagrammatic view, where 20 the filling strands 25 and 27, are shown, the warp strands are removed, to more clearly illustrate the continuity of the filling strands.

At opposite ends of Fig. 4, the filling strands are removed, and each set of warp strands 24a and 24b is indicated by a single line. Warp reinforcing is provided in side bands 28 and 29 and center band 30, by providing pairs of sets of warp strands 24a and 24b at the side of each of the fabric openings, instead of the single sets of warp strands in the wide band 31 between the reinforced bands 28 and 30, and in the wide band 32 between the reinforced bands 30 and 29.

From a broad standpoint, each of the target portions 16 and 18 may be otherwise described as being constituted by open mesh woven yarn fabric.

35 Yarn may be furthermore defined as being either a mono-filament strand or a multi-filament strand, multi-filament strand yarn being spun.

In open mesh woven yarn fabric, in general for use on banner type tow-targets, the yarn may be constituted 40 by filaments of fibres or combinations of filaments and/or fibres of any desired material or materials. Preferably the filaments or fibres are constituted by synthetic materials such as nylon, Orlon, and the like.

45 In the present improved minimized drag banner type tow-target construction, nylon is a preferred material constituting the fabric yarn or strands. The warp strands 24a and 24b and the filling strands 25 and 27 are mono-filament and preferably are 260 denier 4 ply spun nylon yarn.

50 Side-by-side pairs of the monofilament filling strands 25 alternate with side-by-side pairs of the multi-filament strands 26 in the first leading target portion or section 18.

The second trailing portion or section 18 has a length 55 range of from one-sixth ($\frac{1}{6}$) to one-third ($\frac{1}{3}$) the total length of the target 10.

The improved banner type tow-target 10 will fly at an altitude of 30,000 feet and upwards, and at a speed of 60 250 knots per hour and upwards, indicated air speed, with required durability, low drag, and other characteristics including maximum flexibility at extremely low temperatures, and ability to be made radar reflective.

Nylon yarn as above described in the fabric of the improved banner type tow-target 10, has a full 2N leno 65 weave, and provides the desired dimensional stability and flexing capacity in operation as above described under temperature extremes of from -65° F. to $+165^{\circ}$ F.

The improved tow-target 10 furthermore may have all 70 or any portion metallized to provide a radar reflecting target.

Whether the tow-target 10 is metallized, or not, it is desirable to lubricate the target with a preparation to provide in the target maximum flexing capability, and 75 increased resistance to rips and tears.

I claim:

1. A one-piece woven fabric panel for a banner type tow target and the like, the panel including a first portion and a second portion adjacent the first portion, each panel portion having opposite ends and one end of the first panel portion making a junction with one end of the second panel portion, the panel including a plurality of laterally spaced longitudinally extending warp strands, each warp strand extending the entire length of the first and second portions of the panel, the first panel portion having mono-filament filling strands and multi-filament filling strands, and the second panel portion having mono-filament filling strands; the filling strands being longitudinally spaced from each other in the direction of the warp strands; and the mono-filament filling strands being continuous with each other.

2. A one-piece woven fabric panel for a banner type tow target and the like, the panel including a first portion and a second portion adjacent the first portion, each panel portion having opposite ends and one end of the first panel portion making a junction with one end of the second panel portion, the panel including a plurality of laterally spaced longitudinally extending warp strands, each warp strand extending the entire length of the first and second portions of the panel, the first panel portion having mono-filament filling strands and multi-filament filling strands, and the second panel portion having mono-filament filling strands; the filling strands being longitudinally spaced from each other in the direction of the

10

15

20

25

30

warp strands; and the multi-filament filling strands being continuous with each other.

3. A one-piece woven fabric panel for a banner type tow target and the like, the panel including a first portion and a second portion adjacent the first portion, each panel portion having opposite ends and one end of the first panel portion making a junction with one end of the second panel portion, the panel including a plurality of laterally spaced longitudinally extending warp strands, each warp strand extending the entire length of the first and second portions of the panel, the first panel portion having mono-filament filling strands and multi-filament filling strands, and the second panel portion having mono-filament filling strands; the filling strands being longitudinally spaced from each other in the direction of the warp strands; and the mono-filament filling strands being continuous with each other; and the multi-filament filling strands being continuous with each other.
